UNITED STATES PATENT OFFICE.

REGINALD G. W. MAYHOOD, OF SAN LEANDRO, CALIFORNIA.

COMBINATION VENTILATOR AND CANOPY.

Application filed May 10, 1926. Serial No. 108,060.

The present invention relates to improvements in a combination ventilator and canopy and its particular object is to provide a built-in canopy for a kitchen stove or similar appliances which is constructed in such a manner as to serve as a ventilator for the entire room.

Canopies of this character are used in connection with kitchen stoves at the present time, but they extend downwardly below the ceiling and leave an air pocket surrounding the same, which is not subjected to the draft of the canopy. Where the canopy thus depends from the ceiling it also usually happens that its outer wall soon becomes unsightly due to vapors condensing on the same and leaving marks difficult to remove.

In the present invention it is proposed to construct a canopy in such a manner as to be perfectly flush with the ceiling so that the entire room is subjected to the draft of the canopy, there being no air pockets while at the same time the canopy catches the smoke and vapors rising from the stove.

It should be understood that while my combination ventilator and canopy has been described principally in connection with a kitchen stove, a similar construction may render useful service in other connections.

The preferred form of my invention is illustrated in the accompanying drawing in which

Figure 1 shows a top plan view of my combination ventilator and canopy.

Figure 2 a vertical central section through the same.

Figures 3 and 4 enlarged detail views in section of portions of my device.

While I have shown only the preferred form of the invention, I wish to have it understood that various changes or modifications may be made within the scope of the claim attached hereto without departing from the spirit of the invention.

My canopy 1 is made of sheet metal and preferably consists of four side elements 2 slanting downwardly so as to leave a comparatively small opening 3 on top and a large opening 4 at the bottom. The lower

margin of the entire canopy is first turned 50 outwardly as at 6 to present a horizontal flange then turned upon itself as at 7 until it reaches the base of the flange 6 so as to present a double thickness of material while its extreme end is bent downwardly as at 8 55 to form a vertical flange. The canopy is made of a size so as to fit at its lower end between two ceiling joists 9 with the horizontal flange 6 lying against the bottom of the joists so that the entire canopy may 60 be secured to the joists by means of a few nails driven through the double flange. The vertical flange 8 is dimensioned to substantially correspond to the thickness of the ceiling which latter usually consists of laths 11 65 nailed to the joist and plaster 12 secured to the laths and finished in any suitable manner. The lower end of the flange 8 may be curled as shown at 13.

At the neck of the upper end the canopy 70 is turned into a vertical flange 14 then turned upon itself as at 16 and turned again as at 17 to provide a groove into which may be placed the lower end of a transition piece 18 which latter reduces the opening and allows of connection with a cylindrical pipe 75 19. The corners at which the sides 2 join may be re-enforced by means of ribs 21.

The advantages of my combination ventilator and canopy should be readily understood 80 from the foregoing description. After the ceiling joists have been laid, the canopy is placed so that its horizontal flange 6 lies against the bottom faces of the two joists as shown in Figure 2 and is secured in place 85 by the introduction of a number of nails. The transition piece is joined and the pipe joined to the transition piece. The laths and coat of plaster may then be applied and when finished the face of the plaster is substantially flush with the bottom edge of the canopy so that no condensation can deposit 90 on the outside of the canopy while at the same time the entire room is subjected to the draft of the canopy, there being no draft 95 spaces or air pockets. The joints on the inside of the canopy are made so that there is no resistance to the flow of gases. The en-

tire canopy may be made of one sheet of metal and may be pressed into form by a simple operation.

I claim:

In combination, parallel ceiling joists of the character described, a sheet metal canopy having a flange extending outwardly from its bottom end, means for securing the said

flange to the bottom faces of the joists, and a second flange extending downwardly from the inner margin of the first flange, the second flange serving as an abutment for and being co-extensive with a ceiling secured to the bottom of the floor joists.

In testimony whereof I affix my signature.

REGINALD G. W. MAYHOOD.
